UNITED STATES PATENT OFFICE.

LEE E. BEREBAUM, OF CHICAGO, ILLINOIS.

GARMENT-SUPPORTER.

1,152,929.

Specification of Letters Patent. Patented Sept. 7, 1915.

Application filed November 28, 1913. Serial No. 803,458.

To all whom it may concern:

Be it known that I, LEE E. BEREBAUM, a citizen of the United States, residing at Chicago, in the county of Cook and State of Illinois, have invented certain new and useful Improvements in Garment-Supporters, of which the following is a specification.

My invention relates to improvements in garment supporters and has especial reference to devices of this character that are adapted to support the leg portion of socks.

One of the objects of my invention is to provide an all-elastic garment supporter, or garter, comprising a continuous strip of elastic webbing and integral, self-secur ing metallic appurtenances, whereby the fabric portions may frequently and conveniently be renewed in association with the appurtenances that may be used for practically an indefinite period of time.

Another object of my invention is to generally improve the character of the article as a whole and the parts thereof.

Other and further objects of my invention will become readily apparent to persons skilled in the art from a consideration of the following description when taken in conjunction with the drawing, wherein—

Figure 1 is a perspective view of a portion of the leg of the wearer, showing my garter in place, as it will appear on the leg of a relatively lean person. Fig. 2 is a perspective view of one form of clamp that may be made for engaging the upper portion of the sock, or other fabric showing the means of its attachment to the elastic webbing. Fig. 3 is a perspective view of the web-diverging or deflecting slide showing the method of its connection to the protecting pad which underlies both of the slide members when they are clasped together to protect the flesh of the wearer from contact therewith. Fig. 4 is an enlarged cross sectional view, taken on line 4—4 of Fig. 3, showing the manner of removably attaching a pad to the slide. Fig. 5 is a modified form of slide, showing an additional method of increasing the frictional engagement of the elastic webbing with this member. Fig. 6 shows the deflecting slide and another method of connecting the pad thereto. Fig. 7 is a cross sectional view taken on line 7—7 of Fig. 6. Fig. 8 is an enlarged longitudinal vertical view as if taken centrally through Fig. 2. Fig. 9 is a webbing take-up slide having the edges of its parts bent up, as

shown in Fig. 11. Fig. 10 is a modified flat slide of a similar character. Fig. 11 is a transverse section as if taken through the slide, shown in Fig. 9, with the webbing in place. Fig. 12 is a strip of elastic webbing of which the supporter is to be made. Fig. 13 is a view similar to Fig. 1 showing the position of the device on the leg of the wearer as it will appear when worn by relatively rotund persons. Fig. 14 shows the device with the deflecting slides removed, showing how it may be employed by attachment to the shirt or drawers of the wearer, instead of passing around the leg as shown in Figs. 1 and 13.

In all the views the same reference characters are employed to indicate similar parts.

The supporter or garter appurtenances, such as slides, clasps, clamps and fastening members are all provided with self-secur ing, integral means by which they may be attached to the elastic webbing forming the body part of the article, and these parts are adapted and arranged to be attached to and adjusted upon the webbing without the necessity of providing a previously prepared strip of webbing for the purpose, so that these appurtenant parts may be used indefinitely with many renewal strips of webbing thereby effecting considerable economy in the production of the garter and providing an all-elastic and comfortable article, readily and quickly adjustable to meet any conditions that may be presented by the wearer.

In carrying my invention into effect I procure a piece of webbing such as 20 of proper length and elastic throughout its entire extent and such as is usually used for the leg band of garters. To each end of the webbing I secure a fabric clamp member 21—21'. One of the members of the fabric clamp is provided with a laterally extended part 22 having an upper cross bar 23, an intermediate cross bar 24 and slots 25 and 26 within which to pass the webbing 20. The cross bar 24 is provided with two depending spears 27 and 28 which pass downwardly into the slot 26. In attaching the webbing to the clamp 21, it is first passed through the slot 25, under the cross bar 23, over the bar 24, and into the slot 26, the spears 27 and 28 are then passed through the webbing leaving the marginal end on the right side of the fitting. The end 20' is then passed back through the slot 26 without permitting the spears 27 and 28 to pierce it, so

as to cover the ends of the spears from view. The end 20' is then passed back through the slot 25 from the opposite side, until it is included between the cross bar 23 and the 5 main body portion of the webbing 20, as shown very clearly in Fig. 8, thus quickly and conveniently securing each end of the webbing to the respective fabric clamps.

Before both fabric clamps are put on the 10 webbing strip, in the manner heretofore described, the takeup slide 29 is preferably put in place. This slide consists, in part, of three parallel cross bars 30, 31, and 32, the two first are provided with teeth 33 and 34, respectively, which face each other for 15 engagement with the webbing, thus providing slots 35 and 36 between said cross bars. The webbing is placed in the take up slide by first passing it through the slot 35, under bar 31, then up through the slot 36, over bar 29' and back through the slot 36 doubling on itself to form a slack takeup loop 37, which represents for the various 20 adjustments the amount of slack or take up, and then under the bar 31, back into the slot 35, including the slack or take up loop 37, between the bar 29 and the main body portion of the webbing 20, as clearly shown 25 in Fig. 11. By this means the diameter of the leg band, with reference to the fastening members which define it, may be adjusted or, in other words the intervening length of webbing between these members may be varied. The teeth 33 and 34, projecting 30 from the members 30 and 31 respectively, enter the surfaces of the webbing, to a greater or less extent, and produce sufficient friction to prevent movement of the takeup upon the webbing, except when it is intentionally moved thereon, by removing the 35 webbing from engagement with the teeth. To increase or shorten the length of the loop 37 it is only necessary to bend the main body portion of the webbing so that the teeth 34 will not engage it and then exert some tension to increase or decrease the 40 length of the loop and bending the main body portion of the webbing 20 back into position, as shown in Fig. 11.

When the supporter has been made in the manner described it may conveniently be used as shown in Fig. 14 wherein the length of webbing between the end fabric clamps 21-21' may be varied by the takeup device just described.

In Fig. 10, which is a modification of the device shown in Fig. 9, only one set of engaging teeth are shown and in some instances this may be sufficient for effecting 60 all of the necessary holding friction required between the various convolutions of the webbing or strip which passes through the device.

The web deflecting clasp slides 39 and 40, 65 of which there are a pair for each garter,

are employed to join the ends of the leg band and are adjustable to permit variation of the length of the pendant portions 41 and 42 of the webbing, as indicated by comparing Figs. 1 and 13. These clasps permit 70 diverging of the tape from a substantial horizontal to a substantial vertical plane and are adapted to be secured together by suitable fastening devices, of which the drawings show a hook 43 on one member and 75 an eye 44 in the other. One of these members carries a protecting pad 45, preferably made of leather, and secured to the clasp in any suitable manner. In Figs 6 and 7 rivets 46, are shown for this purpose, while 80 in Figs. 3 and 4 a means of attachment permitting the renewal of the pad 45 is indicated. Portions 48 of the body part of the clasp 40 are deflected or kinked laterally, as shown more clearly in Fig. 4, and 85 these portions are perforated for reception of a common pin 49. A smaller deflection 50 is made at the end of this series of the deflected parts to permit of a recess for reception of the pin head 49'. The body part 90 of the clasp is perforated to receive the deflected portions of the pad 45', through which the pin may be inserted for securing it to the clasp. The deflection 48 on the 95 opposite end of the slide in which the head of the pin 49' is placed, serves as a guard for the point of the pin. To renew the pad 45 it is only necessary to pull the pin out and to separate the plate from the pad when 100 a new pad may be inserted. The deflections 50 of the pad may be placed in the perforations of the plate and the pin inserted through them as before.

The webbing deflecting clasps 39 and 40 may be placed upon the webbing without the necessity of slipping the ends of the webbing through the slots. If one side of the webbing is placed in the slot 51 and passed into the slots 52 and 53 and subsequently 105 the other side of the webbing be placed under the projection 54 and into the other end of the same slots the clasp may thus be conveniently and quickly placed upon the webbing and removed therefrom. The teeth 55 engage the webbing 20 and serve as means 110 for holding it in proper position to prevent its longitudinal movement upon the webbing strip. The device in Fig. 5 shows an additional means for holding the clasp in 115 position on the band in which it has been placed. The ends of the slot 53' are tapered at sharp angles so that the band is slightly compressed thereby when it enters the space between the adjacent tapered walls bounding the ends of the slots. This means of securing the band may be used in conjunction with the teeth 55, or may be used alone, as desired.

It is evident, from the foregoing description, that the leg band of the garter may be 120

varied in diameter by use of the take-up clasp 32 and that the pendant ends 41 and 42 of the garter may be varied in length by means of the adjusting clasps 39 and 40 and it is 5 further evident, that the fittings or appurtenances used upon the garter may be conveniently and quickly assembled upon a new band of webbing to constitute a new garter without the necessity of previously preparing 10 the band.

While I have herein shown and described a single embodiment of my invention for the purpose of clear disclosure it is evident that changes may be made in the various parts, 15 within the scope of the appended claims, without departing from the spirit of my invention.

Having described my invention, what I claim is:—

20 1. An elastic, leg-encircling hose supporter, comprising a strip of webbing, fabric-engaging clamps secured respectively to opposite ends thereof, and a pair of clasps having mutual engaging means, each said 25 clasp having web-engaging-and-deflecting portions fixing the clasp in adjusted position on the strip and deflecting the contiguous strip-end into pendant position, whereby the respective lengths of the leg-encircling portion and the pendant-portions of the strip are fixedly defined.

20 2. An elastic, leg-encircling hose supporter, comprising a strip of webbing, fabric-engaging clamps secured respectively to opposite ends thereof, a pair of clasps having mutual engaging portions, each said clasp having web-engaging-and-deflecting portions fixing the clasp in adjusted position on the strip and deflecting the contiguous strip-end into pendant position, and a 35 loop-retaining take-up engaging a looped portion of the strip between the two clasps.

3. An elastic hose supporter comprising a strip of webbing, fabric engaging clamps secured respectively to opposite ends of said strip, and a pair of clasps having mutual engaging means, each said clasp laterally

attachable and detachable with respect to the mid-length of the web and having web-engaging-and-deflecting portions fixing the 50 clasp in adjusted position on the strip and deflecting the contiguous strip end into pendant position, whereby attachment of the clasps fixedly defines the respective lengths of the leg encircling portion and the 55 pendant portions of the strip, as a leg encircling garter; and removal of the clasps converts the structure into a drawers garter.

4. A hose supporter comprising a single strip of elastic webbing, fabric-engaging 60 clamps secured respectively to opposite ends thereof, and a pair of clasps having mutual engaging means, each said clasp having two convergent slots and a cross slot connecting said convergent slots, each said clasp effecting laterally-removable, longitudinally-adjustable, non-sliding engagement with the strip; and deflecting the contiguous strip end into pendant position at an acute angle to the leg encircling strip portion, whereby 70 the respective lengths of the leg encircling portion and the pendant portions of the strip are fixedly defined, and whereby the clasps are laterally removable from the strip to convert the structure into a drawers 75 garter.

5. As an article of manufacture, a supporter of the character described comprising a pair of mutually engaging clasps, each comprising a plate provided with a 80 vertical slot, tape gripping means, a diagonal deflecting slot and a cross connecting slot connecting said vertical and diagonal slots; a single continuous tape engaged and deflected between its ends by said clasps, 85 and fabric engaging clamps on the extremities of said tape.

In testimony whereof I hereunto set my hand in the presence of two witnesses.

LEE E. BEREBAUM.
